CLAIM

I claim the ornamental design for the foldable support for mobile devices, as shown and described.

DESCRIPTION

FIG. 1 is a top perspective view of a foldable support for mobile devices in an unfolded configuration;

FIG. 2 is a top view of the foldable support for mobile devices;

FIG. 3 is a bottom view of the foldable support for mobile devices;

FIG. 4 is a left-side view of the foldable support for mobile devices;

FIG. 5 is a right-side view of the foldable support for mobile devices;

FIG. 6 is a front view of the foldable support for mobile devices;

FIG. 7 is a rear view of the foldable support for mobile devices; and,

FIG. 8 is a top perspective view of the foldable support for mobile devices in a folded configuration.
